(57) **CLAIM**

The ornamental design for a tray with mounting bracket, as shown and described.

DESCRIPTION

FIG. 1 is a top, front, and right side perspective view of a tray with mounting bracket showing our new design;
FIG. 2 is a bottom, rear, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a partial, enlarged bottom, rear, and left side perspective view thereof, with the remaining portions omitted for clarity of illustration; and,

FIG. 10 is a partial, enlarged top, rear, and left side perspective view thereof, with the remaining portions omitted for clarity of illustration.

The broken-line disclosure in the views is understood to represent unclaimed portions of the tray.
